UNITED STATES PATENT OFFICE.

HOWARD TERHUNE, OF EAST CLEVELAND, OHIO, ASSIGNOR TO THE KILBY MANUFACTURING COMPANY, OF CLEVELAND, OHIO, A CORPORATION OF OHIO.

DROP HAMMER.

Application filed October 20, 1919. Serial No. 331,889.

To all whom it may concern:

Be it known that I, HOWARD TERHUNE, a citizen of the United States, residing at East Cleveland, in the county of Cuyahoga and State of Ohio, have invented a certain new and useful Improvement in Drop Hammers, of which the following is a full, clear, and exact description, reference being had to the accompanying drawings.

10 This invention relates to drop hammers and has for its object the provision of a new, improved, and simplified construction whereby the movable member of the hammer may be laterally adjusted relatively to 15 the fixed member thereof and retained in adjusted position notwithstanding the excessive shocks and strains to which devices of this class are subject. My invention is independent of the particular nature or 20 mode of operation of the hammer, and thus is equally applicable to steam hammers and to board hammers. Such devices when employed for the making of drop forgings are generally equipped with mating dies, one 25 part of which is rigidly attached to the anvil or base of the hammer, and the other part of which is attached to the movable head thereof. Owing to the method of attaching these die members to the respective 30 parts of the hammer, which is generally accomplished by means of wedges or keys, since only devices of such simplicity and strength are capable of withstanding the stresses to which such devices are subjected, 35 and owing also to inaccuracies in fashioning the exterior portions of the dies themselves, it is frequently found that when the two die members are secured in place they will fail of accurate registering with each other by 40 a small amount, and in order to bring them into the correct relative relation it has long been the custom to shift the entire top structure of the machine relatively to the base or anvil. At the same time it is impossible 45 to attach these parts rigidly to each other after the adjustment is complete, else the force of the recoil and the vibrations caused by the hammer blow would cause the fracture of some of the parts. Accordingly the 50 objects of the present invention are the provision of means of great simplicity and strength whereby the above described adjustment can be secured and whereby after adjustment the parts may have the necessary freedom of movement without impair-

ment of such adjustment; and other objects and advantages of the invention will become apparent as the description proceeds.

In the drawings accompanying and forming a part of this application I have illustrated one embodiment of my invention, although it will be understood that these drawings are illustrative of only one of the many physical structures in which my inventive idea may be utilized. In these drawings Fig. 1 is a front elevation of a portion of a drop hammer embodying my improvements, one side of the device being shown in section; Fig. 2 represents a side elevation of the parts shown in Fig. 1; and Fig. 3 is a horizontal sectional view taken upon the broken line 3—3 of Fig. 1.

Describing the parts by reference characters, the base or anvil of the hammer consists of a massive metal block 1 having at opposite sides the elevated portions 2—2 defining between them a channel 3 in which the anvil cap or shoe 4 is locked by means of the key 5 wedged therein. This shoe is in turn provided with a suitable groove 6 for the reception of the stationary die member (not shown).

Each of the portions 2—2 is formed with an upwardly facing supporting surface 8 in which is formed the transverse groove 9, whose inner end opens adjacent the shoe 4 and whose outer end opens into the pocket 10. Outside of this pocket the base member is formed with an abutment 11 which rises above the surface 8.

Seated upon the portions 2—2 are the uprights 12—12 whose inner faces are provided with the parallel guideways 13—13 between which is slidably mounted the hammer 14. This hammer is operated in any suitable manner, the means for accomplishing this not being shown herein since my invention is independent thereof. Its lower face is shown as provided with a groove 15 for the reception of the movable member of the die (not illustrated). The lower end of each upright is provided with a foot 16 having a surface complementary to and resting on the surface 8 and also having a tongue 17 fitting in the groove 9. The outer face of each upright is provided at the point opposite to the abutment 11 with a thrust-surface 18, and the adjacent face of the abutment is formed with a complementary thrust-surface 19. Between the

surfaces 18 and 19 I interpose a wedge member 20, preferably arranged in vertical position and preferably provided with a vertical stem 21 which is adjustably secured 5 to one of the parts between which the wedge is interposed. As shown here this stem traverses a suitable ear 22 carried by the upright 12 and is held in adjusted position relatively thereto by suitable nuts 24—24. 10 This stem has the double function of holding the wedge in adjusted position and also maintaining it in the proper position relatively to the surfaces which it engages, preventing it from becoming canted and ensuring 15 at all times a maximum of surface contact; this end being further insured, if desired, by forming the rearward side of the wedge and the surface 18 which it contacts with the cooperating tongue and groove 23. 20 The foot 16 is formed with a notch 25 giving access to this wedge and affording room for the abutment 11, and the wedge is preferably provided at its upper end with a projecting shoulder 26 to facilitate its loosening or adjusting by hammering if and when required.

The uprights are secured to the base by suitable bolts 30—30 and 31—31. The former pass obliquely from the inward portions 30 of the feet 16—16 downwardly and outwardly through the base where they are secured by nuts 32 having springs 33 interposed therebeneath; the bolts 31 are shown as passing vertically downward through the 35 outer portion of the feet 16 and the overhanging part of the base and secured by nuts 34 having springs 35 interposed therebeneath. The holes through which the bolts pass are made extra large so as to permit a 40 considerable amount of relative movement.

In the present embodiment I have shown the surfaces 18 as vertical and the surfaces 19 as inclined, and this is my preferred construction although not imperative, since 45 the inclinations can be reversed, or both sides made inclined. In order to adjust the hammer-top relatively to the base one of the wedges is loosened and the other one tightened, care being exercised not to tighten 50 both wedges to an extent sufficient to converge the guideways and pinch the hammer. I have illustrated no connection between the lower ends of the uprights, since the inclination of the bolts 30—30 is sufficient to produce the small force-component 55 necessary to keep these members apart and in contact with their respective wedges; although I do not restrict myself to this construction. The arrangements here shown 60 permit the necessary looseness of the parts to absorb the recoil and rebound and vibration of the parts, while insuring that at the end of each blow the various parts will return to their initial position; the large bearing surface provided by my adjustment 65

means affording a maximum of strength and a minimum of wear.

It will be understood that many changes in details and constructions can be made without departing from my inventive idea, 70 wherefore I do not limit myself to the details herein shown except as specifically recited in the claims hereto annexed.

Having thus described my invention, what I claim is:—

1. In a drop hammer, the combination with a base and uprights mounted thereon, of a wedge member separate from both base and upright interposed between each of said uprights and a part of said base, and adapted to hold the uprights against movement laterally outwardly relatively to the base while permitting free upward movement of said uprights. 80

2. In a drop hammer, the combination with a base and uprights seated thereon, said base having at each side an inwardly facing abutment, of a wedge interposed between each abutment and its corresponding upright whereby said upright may be held 90 against outward movement laterally relatively to said base. 85

3. In a drop hammer, the combination with a base and uprights seated thereon, said base having at each side an inwardly facing abutment, of a wedge interposed between each abutment and its corresponding upright whereby said upright may be held 95 against outward movement laterally relatively to said base, and means for securing said wedge rigidly to one of the parts between which it is interposed. 100

4. In a drop hammer, the combination with a base and uprights mounted thereon, said base having at each side an inwardly facing abutment, of a wedge interposed between each abutment and its corresponding upright whereby said upright may be held 105 against outward movement laterally relatively to said base, the contacting face of said wedge adjacent to said upright being substantially vertical. 110

5. In a drop hammer, the combination with a base and uprights seated thereon, of a wedge interposed between each of said uprights and a part of said base, said wedge having its thickest portion uppermost and being movable vertically, and means for preventing movement of said wedge in lateral and angular directions. 115

6. In a drop hammer, the combination with a base and uprights seated thereon, said base having at each side an inwardly facing abutment, of a vertical wedge interposed between each abutment and its corresponding upright, and means for securing said wedge to one of the parts between which it is interposed. 125

7. In a drop hammer, the combination with a base having an upwardly facing sup- 130

- porting surface and an abutment projecting above such surface, of an upright mounted on said surface at one side of said abutment, a wedge interposed between said abutment and the adjacent face of said upright and having its thickest portion uppermost, and a stem projecting vertically from said wedge and adjustably secured to one of the parts between which it is interposed.
- 10 8. In a drop hammer, the combination with a base having an upwardly facing supporting surface and a laterally facing abutment, said surface having a well adjacent said abutment, of a vertical wedge interposed between said abutment and upright and lying at least partially in said well, and means adjustably securing said wedge to one of the members between which it is interposed.
- 20 9. In a drop hammer, the combination with a base having an upwardly facing supporting surface and a laterally facing abutment, said surface having a well adjacent said abutment, of a vertical wedge interposed between said abutment and upright, and means adjustably securing said wedge

to one of the members between which it is interposed, the face of the wedge being substantially vertical upon the side presented to that member to which it is secured. 30

10. In a drop hammer, the combination with a base having an upwardly facing supporting surface and a laterally facing abutment projecting above said surface, of an upright having a foot which rests on said surface and is notched for the reception of said abutment, and a vertical wedge interposed between the base of such notch and the face of said abutment. 35

11. In a drop hammer, the combination with a base having an upwardly facing supporting surface and a laterally facing abutment, of an upright having a foot resting on said surface and a surface facing said abutment, said base and foot being formed 40 with tongue and groove perpendicular to said abutment, and wedge means interposed between said abutment and the surface of said upright which faces the same.

In testimony whereof, I hereunto affix my 50
signature.

HOWARD TERHUNE.
